UNITED STATES PATENT OFFICE.

HENDRIK STUKART, OF CHICAGO, ILLINOIS, ASSIGNOR TO U. S. SLICING MACHINE COMPANY, OF CHICAGO, ILLINOIS, A CORPORATION OF ILLINOIS.

SLICING-MACHINE.

1,106,591.

Specification of Letters Patent. Patented Aug. 11, 1914.

Application filed July 18, 1913. Serial No. 779,675.

To all whom it may concern:

Be it known that I, HENDRIK STUKART, a subject of the Ruler of the Netherlands, and resident of Chicago, in the county of Cook 5 and State of Illinois, have invented certain new and useful Improvements in Slicing-Machines, of which the following is a specification.

This invention relates in general to improvements in slicing machines of the type embodying a reciprocating carriage and an article support mounted upon the carriage and adapted to be intermittently advanced with respect to the carriage to present a new 10 portion of the article to the cutter, and one of the objects of the invention is to provide an improved machine of this class, having means for automatically returning the article support with respect to the carriage.

20 To the attainment of these ends and the accomplishment of other new and useful objects as will appear, the invention consists in the features of novelty, in substantially the construction, combination and arrangement of the several parts, hereinafter more fully described and claimed and shown in the accompanying drawings, exemplifying the invention, and in which,—

Figure 1 is a top plane view of a slicing machine, having an attachment applied thereto, constructed in accordance with the principles of this invention, and with parts removed and parts broken away; for the sake of clearance; Fig. 2 is a longitudinal 30 sectional view as taken on line 2—2 of Fig. 1; Fig. 3 is a sectional view as taken on line 3—3 of Fig. 1; Fig. 4 is a detail view in elevation of a portion of the feeding mechanism.

40 Referring more particularly to the drawings, the carriage designated generally by the reference numeral 10 moves adjacent the cutter 11, and is reciprocated upon the guides 12, 13, by means of a crank 14 connected to a shaft 15 supported by the base 16, and which crank is connected by means of a link 17 with the carriage, so that when the hand wheel 18 is operated, the shaft 15 will be rotated, and a reciprocating movement will be imparted to the carriage.

50 A shaft 19 is journaled in suitable bearings 20, carried by the carriage 16 and this shaft is located below, and preferably adjacent the center of the meat table to be

hereinafter described. Arranged adjacent 55 one end of the shaft 19 is a clutch element 21, which is secured to the shaft for rotation therewith by means of a suitable fastening device 22. A sleeve 23 is mounted loosely upon the shaft 19 and connected with the 60 sleeve is another clutch element 24 which co-operates with the clutch element 21. This sleeve 23 is adapted to be shifted longitudinally on the shaft 19 by means of a crank arm 25, which is connected with a shaft 26 65 journaled in suitable bearings, and which crank arm is provided with a projection 27 entering a circumferential groove 28 in an enlarged portion 29 arranged preferably adjacent the other end of the sleeve 23. This 70 enlarged portion 29 is provided with a clutch face 30, which co-operates with another clutch element 31 mounted loosely upon the shaft 19. This clutch element 31 is mounted loosely upon a sleeve 32 having an enlarged 75 portion 33 and the sleeve 32 is in turn connected with a sleeve 34 for rotation therewith, the latter being directly journaled upon the shaft 19, and having connected thereto a pinion 35, which pinion meshes 80 with a rack carried by the lower face of the guide 13, so that as the carriage is reciprocated the pinion 35 will be rotated first in one direction and then in the other, according to the direction of movement of the 85 carriage.

A yielding connection is provided between the clutch element 31 and the sleeve 32, preferably in the form of spring controlled pins 36, which engage in co-operating teeth 37 on 90 the adjacent face of the enlarged portion 33 of the sleeve. This yielding connection is provided for the purpose of preventing movement of the meat plate upon the movement of the support to the right in Fig. 1, 95 which movement of the support would cause the meat plate to move forward, but to permit movement of the meat plate upon the completion of the cutting stroke and the beginning of the return stroke to retract the 100 same until the actuation of the lever 58 by the pin 60.

Mounted upon the sleeve 23 is a worm gear 38 which is connected to the sleeve for rotation therewith by means of keys or feathers 105 39, and the worm gear is of such a length that the sleeve 23 may be shifted longitudinally with respect to the shaft 19 and also

with respect to the worm gear. In order to hold the gear against longitudinal movement during the shifting of the sleeve, the worm gear is provided with a portion having a circumferential groove 40 into which a projection 41 on the carriage 16 extends, thereby permitting the worm gear to rotate with the sleeve, and holding it against movement longitudinally when the sleeve is shifted.

10 Meshing with the worm gear 38 is a worm 42 which latter rotates about an axis 43 arranged at right angles to the shaft 19, and connected with this worm 42 for rotation therewith is a pinion gear 44, which meshes 15 with a rack 45 carried by the bottom of the feed table 46, and which latter has a bearing directly upon the carriage 16, as shown more clearly in Fig. 3. Thus it will be manifest that when the shaft 19 is rotated, the sleeve 20 23 will be rotated. This in turn will impart a rotary movement to the worm 38, which latter rotates the worm 42 and in turn the pinion gear 44, thereby causing the feed table 46 to be advanced or retracted with 25 respect to the carriage 16 according to the direction of rotation of the worm 38.

The feed table 46 is held against displacement with respect to the carriage 16 in any suitable manner,—a simple and efficient 30 means embodies pins 46' which project through portions of the carriage 16 and into grooves 47 in the adjacent faces of the feed table and which grooves extend longitudinally of the table, so that the reciprocating 35 movement of the feed table with respect to the carriage will not be interfered with. Elastic elements 48 are provided for holding the pins in position and screws 49 are also provided for holding the elastic elements 40 against displacement.

A meat plate 50 is arranged above the feed plate 46 and has a bearing directly upon the carriage 16, and this plate 50 is connected with the feed table in any suitable manner, such as by means of a separable fastening device 51, although any form 45 of fastening device may be employed.

An intermittent movement is imparted to the shaft 19 preferably by means of a ratchet 50 gear 52, secured to the shaft, and with which gear a dog 53 coöperates. This dog is mounted upon an arm 54 pivotally supported preferably by the shaft 19, and an extension 55 on the arm carries an anti-friction device 56 which coöperates with a cam 57 secured to any fixed portion of the machine so that when the carriage is reciprocated, the anti-friction device will pass across the cam 57 and move the dog in a direction such that it will coöperate with the teeth of the ratchet 52 and thereby impart a step of rotation to the shaft 19. A crank 58 may also be connected with the shaft 19 for rotating it.

65 With the mechanism thus far described,

it will be manifest that as the carriage is reciprocated, the pinion 35, which is in engagement with the rack on the guide 13, will be rotated in first one direction and then the other, and as long as the clutch elements 30 and 31 are out of engagement with each other this motion of the pinion 35 will have no effect upon the shaft 19, and during this time the pawl and ratchet elements 53, 52, will intermittently operate the shaft 19 and 75 if the clutch elements 21, 24, are in engagement with each other, the feed plate will be advanced to present a new portion of the uncut material to the cutter. In order, therefore, to utilize this motion of the pinion 35 to return the feed and meat plates, all that is necessary is to disconnect the clutch elements 21, 24 and move the clutch elements 30, 31 into operative relation. In this position, the motion imparted to the pinion 35 by the rack on the guide 13, will rotate the worm 38 and consequently the worm 42 and pinion 44 in the opposite direction, and the pinion 44 will, through the medium of the rack 45, automatically return the 90 meat and feed plates.

To automatically render the respective clutch elements active and inactive and to shift the sleeve 23, the crank shaft 26 and crank 25 are provided, and these are automatically rocked by means of an arm 58, which is connected to the crank shaft 26, and is arranged beneath the feed plate 46. Spaced projections 59, 60 are arranged on the bottom of the feed plate between which the arm 58 extends, and these projections are so disposed with respect to each other that just as the feed plate is about to reach the limit of its forward movement one of the projections will engage the arm 58 to shift 135 it and rock the shaft 26 to move the sleeve 23 in one direction, and when the feed plate is about to reach the limit of its movement in the opposite direction, the other projection will engage and shift the arm 58 as well as 119 the sleeve 23. Thus, it will be manifest that the sleeve 23 will be automatically shifted by the movement of the feed plate with respect to the carriage, and this automatic shifting of the sleeve in one direction will 115 render active the parts which will connect the pinion 35 with the sleeve 23 and thereby automatically and positively return the feed plate.

In order to insure a positive action of the 120 sleeve 38, a lever 61 is provided which is connected with the crank shaft 26 and is provided with a projection 62 and a second lever 63 having a tapered or cam-shape portion 64 is arranged at right angles with the 125 lever 61 and an elastic member 65 is connected with the lever 63 and a fixed portion of the carriage and operates to normally hold the tapered portion 64 of the lever in engagement with the projection 62 on the 130

lever 61. When the extremity of the tapered portion 64 is in contact with the projection 62, the sleeve 23 will be held in an intermediate position, that is, so that the clutch elements 21, 24 and 30, 31 will be inactive with respect to each other. When, however, the arm 58 is shifted and the shaft 26 rocked, the projection 62 of the lever 61 will be shifted and the spring 65 will cause one or the other of the inclined portions or faces 64 to move against the projection 62 and thereby assist in shifting the sleeve 23.

In order to return the feed plate from any point to which it has been advanced, and at any time, the lever 61 is provided with a handle 66 arranged in a convenient position for the operator, and which may be grasped by the operator and shifted when desired.

In order to prevent overthrow of the shaft 19, under the influence of the pawl and ratchet mechanism, a friction device 67, controlled by an elastic member 68 may be provided, and which cooperates with the shaft 19.

With this improved construction it will be manifest that all of the parts are compactly arranged and the feeding mechanism is not only mounted upon the carriage, but is concealed and protected thereby, the only portion of the feeding mechanism which projects above the top of the carriage 16 being the pinion 44, and this pinion is itself protected and covered by the feed plate, the latter being of such a length that the pawl and ratchet mechanism will also be covered and protected thereby in any position of the feed plate with respect to the carriage.

While in the present exemplification of this invention the preferred form or construction and arrangement of the several parts are herein shown and described, it is to be understood that numerous changes may be made in the details of construction and in the combination and arrangement of the several parts, without departing from the spirit of this invention.

With this improved arrangement of feed plate and meat plate, it will be apparent that one or both may be readily removed or attached without interfering with any of the remaining portions of the mechanism.

What is claimed as new is:

1. The combination of a relatively movable article support and cutter, a feed plate connected with the support for movement with respect thereto, means for moving the plate in a feeding direction with respect to the support, and means operating to automatically return the feed plate with respect to the support when the plate has been advanced to a predetermined point with respect to the support.

2. The combination of a relatively movable article support and cutter, a feed plate connected with the support for movement

with respect thereto, means for moving the feeding plate in one direction with respect to the support, and means controlled by such movement of the plate for moving the plate in another direction with respect to the support. 70

3. The combination of a relatively movable article support and cutter, a feed plate connected with the support for movement with respect thereto, means for moving the feeding plate in one direction with respect to the support, and means controlled by such relative movement of the plate and the support for automatically returning the feeding plate with respect to the support. 75

4. The combination of a relatively movable article support and cutter, a feed plate, movable with the support, said plate and support being capable of relative movement, means for effecting a relative movement of the support and plate to move the article in one direction, and provisions whereby a portion of the said means will effect another relative movement of the support and plate when the plate has been moved to a predetermined point with respect to the support. 80

5. The combination of a relatively movable meat support and cutter, a feed plate mounted for movement with respect to the support and in two different directions, and provisions embodying a controlling element for automatically effecting such movements of the plate upon the movement of the latter to a predetermined position with respect to the support. 95

6. The combination of a cutter, a support having a forward and a backward movement, a feed plate carried with the support for movement with respect thereto, means for moving the plate in a feeding direction with respect to the support, and means operating to automatically return the feed plate with respect to the support when the plate has been advanced to a predetermined point with respect to the support. 100

7. Article feeding mechanism for slicing machines, embodying a support having a forward and a return movement, a feed plate carried therewith and movable with respect thereto, positive means for moving the plate in one direction with respect to the support, positive means for moving the plate in another and different direction with respect to the support, a rotatable element, and provisions for automatically and alternately connecting the said means with the rotatable element. 115

8. Article feeding mechanism for slicing machines, embodying a support having a forward and a return movement, a feed plate carried therewith and movable with respect thereto, means for advancing and means for returning the plate with respect to the support, a rotatable element, and means controlled by the movement of the 120

plate and operating to automatically and alternately connect the said advancing and returning means with the said element.

9. Article feeding mechanism for slicing machines, embodying a support having a forward and a return movement, a feed plate carried therewith and movable with respect thereto, means for advancing and means for returning the plate with respect to the support, a rotatable element, and means operating at a predetermined point in the travel of the plate with relation to the support, for controlling the said advancing and returning means with respect to said element.

10. Article feeding mechanism for slicing machines, embodying a support having a forward and a return movement, a feed plate carried therewith and movable with respect thereto, positive means for advancing and positive means for returning the plate, and provisions for automatically controlling both of the said means.

11. Article feeding mechanism, for slicing machines, embodying a support having a forward and a return movement, a feed plate carried therewith and movable with respect thereto, means for advancing and means for returning the plate, a controlling element for the advancing and returning means, and means whereby the movement of the plate in either direction will automatically render active the mechanism for moving the plate in the opposite direction.

12. Article feeding mechanism for slicing machines, embodying a support having a forward and a return movement, a feed plate carried therewith and movable with respect thereto, positive means for advancing and positive means for returning the plate, controlling means for rendering active the said advancing and returning means, and means operatively connected with the said plate for actuating the said controlling means.

13. Article feeding mechanism for slicing machines, embodying a support having a forward and a return movement, a feed plate carried therewith and movable with respect thereto, positive means for advancing and positive means for returning the plate, actuating mechanism therefor embodying a shiftable controlling element, and means connected with the plate and operating at predetermined points in the movement of the plate with respect to the support to shift the said element.

14. Article feeding mechanism for slicing machines, embodying a support having a forward and backward movement, a feed plate carried therewith and movable with respect thereto, advancing and retracting means for the plate embodying an element adapted to be automatically set for controlling the direction of movement of the plate with respect to the support.

15. The combination of a reciprocating support, a feed plate connected therewith and movable relatively to the support, means for advancing and retracting the plate with respect to the support and embodying a shiftable element for controlling the direction of movement of the plate, and means whereby such relative movement of the plate will shift the said element. 70

16. The combination of a reciprocating support, a feed plate connected therewith and movable relatively to the support, means for advancing and retracting the plate with respect to the support and embodying a shiftable element for controlling the direction of movement of the plate, and means movable in unison with the plate and operating to automatically shift the said element at a predetermined point in the movement of the plate. 80

17. Article feeding mechanism for slicing machines, embodying a support having a forward and a return movement, a feed plate carried therewith and movable with respect thereto, a rotatable element for advancing and retracting the plate with respect to the support, and means for automatically controlling the direction of movement of the plate. 90

18. Article feeding mechanism for slicing machines, embodying a support having a forward and a backward movement, a feed plate carried therewith and movable with respect thereto, positive means for advancing and retracting the plate with respect to the support, and means for automatically changing the direction of movement of the plate, at one or more predetermined points in the movement of the plate. 95

19. Article feeding mechanism for slicing machines, embodying a support having a forward and a backward movement, a feed plate carried therewith and movable with respect thereto, a rotatable element for advancing and retracting the plate with respect to the support, and means operating to automatically control the direction of movement of the plate, all of said parts being located substantially below the plane of the plate. 105

20. Article feeding mechanism for slicing machines, embodying a support having a forward and a backward movement, a feed plate carried therewith and movable with respect thereto, positive means for advancing and retracting the plate with respect to the support, and means embodying a clutch device for automatically controlling the direction of movement of the plate. 115

21. Article feeding mechanism for slicing machines, embodying a support having a forward and a backward movement, a feed plate carried therewith and movable with respect thereto, a prime mover for advancing and retracting the plate with respect to the support. 125

- the support, and means embodying a shiftable element for controlling the direction of movement of the plate and with respect to which prime mover, the shifting of the said element is automatic. 5
22. Article feeding mechanism for slicing machines, embodying a support having a forward and a backward movement, a feed plate carried therewith and movable with respect thereto, a prime mover for advancing and retracting the plate with respect to the support, means embodying a shiftable element for controlling the direction of movement of the plate and with respect to which prime mover, the shifting of the said element is automatic, and manual means for also actuating the said prime mover. 10
23. Article feeding mechanism for slicing machines, embodying a support having a forward and a backward movement, a feed plate carried therewith and movable with respect thereto, a rotatable element for advancing and retracting the plate with respect to the support, mechanism for actuating the element embodying provisions for rotating it in opposite directions, and mechanism for automatically controlling the direction of rotation of the element. 15
24. Article feeding mechanism for slicing machines, embodying a support having a forward and a backward movement, a feed plate carried therewith and movable with respect thereto, a rotatable element for advancing and retracting the plate with respect to the support, mechanism for actuating the element embodying provisions for rotating it in opposite directions, and means whereby the direction of rotation of the element will be automatically controlled by the movement of the plate. 20
25. Article feeding mechanism for slicing machines, embodying a support having a forward and a backward movement, a feed plate carried therewith and movable with respect thereto, a rotatable element for advancing and retracting the plate with respect to the support, mechanism for actuating the element embodying provisions for rotating it in opposite directions, and means whereby the direction of rotation of the element will be automatically controlled by the movement of the plate, all of the parts being disposed below the plate. 25
26. Article feeding mechanism for slicing machines, embodying a support having a forward and a backward movement, a feed plate carried therewith and movable with respect thereto, an element rotatable about an upright axis for advancing and retracting the plate with respect to the support, and mechanism for actuating the element in opposite directions and embodying a shiftable element, and with respect to which first recited element the shifting of the second recited element is automatic. 30
27. Article feeding mechanism for slicing machines, embodying a support having a forward and a backward movement, a feed plate carried therewith and movable with respect thereto, an element rotatable about an upright axis for advancing and retracting the plate with respect to the support, and mechanism for actuating the element in opposite directions and embodying a shiftable element, and means moving in unison with the plate and operating to automatically shift the second recited element. 70
28. Article feeding mechanism for slicing machines, embodying a reciprocating support, a feed plate connected therewith, means for moving the plate relatively to the support, the said means embodying two cooperating and relatively movable elements normally inactive with respect to the plate, one of the elements being movable with and the other being separate from and fixed with relation to the support, and means whereby the movement of the plate will automatically render the first said means active. 75
29. Article feeding mechanism for slicing machines, embodying a reciprocating support, a feed plate connected therewith, means for moving the plate relatively to the support, the said means embodying a rack and pinion normally inactive with respect to the plate, said rack and pinion being, one connected and movable with the support, and the other being fixed and with relation to which the support has a relative movement, and means for automatically rendering the first recited means active with respect to the plate. 80
30. Article feeding mechanism for slicing machines, embodying a reciprocating support, a feed plate connected therewith, means for moving the plate relatively to the support, the said means embodying a rack and gear, and normally inactive with respect to the plate, said gear and rack being one connected and movable with the support, and the other being fixed and with relation to which the support has a relative movement, and means for automatically rendering the first said means active and inactive, at predetermined points in the movement of the plate. 85
31. Article feeding mechanism for slicing machines, embodying a reciprocating support, a feed plate movable therewith and with respect thereto, means for moving the plate with respect to the support, the said means embodying a gear and rack normally inactive with respect to the plate, one of which is movable with the support, the other being separate from the support and with respect to which the support is relatively movable, and provisions for automatically rendering the said means active and inactive with respect to the plate. 90
32. Article feeding mechanism for slicing machines, embodying a reciprocating support, a feed plate connected therewith, means for moving the plate relatively to the support, the said means embodying a rack and pinion normally inactive with respect to the plate, said rack and pinion being, one connected and movable with the support, and the other being fixed and with relation to which the support has a relative movement, and means for automatically rendering the first recited means active with respect to the plate. 95
33. Article feeding mechanism for slicing machines, embodying a reciprocating support, a feed plate connected therewith, means for moving the plate relatively to the support, the said means embodying a rack and gear, and normally inactive with respect to the plate, said gear and rack being one connected and movable with the support, and the other being fixed and with relation to which the support has a relative movement, and means for automatically rendering the first said means active and inactive, at predetermined points in the movement of the plate. 100
34. Article feeding mechanism for slicing machines, embodying a reciprocating support, a feed plate connected therewith, means for moving the plate relatively to the support, the said means embodying a rack and gear, and normally inactive with respect to the plate, said gear and rack being one connected and movable with the support, and the other being fixed and with relation to which the support has a relative movement, and means for automatically rendering the first said means active and inactive, at predetermined points in the movement of the plate. 105
35. Article feeding mechanism for slicing machines, embodying a reciprocating support, a feed plate connected therewith, means for moving the plate relatively to the support, the said means embodying a rack and gear, and normally inactive with respect to the plate, said gear and rack being one connected and movable with the support, and the other being fixed and with relation to which the support has a relative movement, and means for automatically rendering the first said means active and inactive, at predetermined points in the movement of the plate. 110
36. Article feeding mechanism for slicing machines, embodying a reciprocating support, a feed plate connected therewith, means for moving the plate relatively to the support, the said means embodying a rack and gear, and normally inactive with respect to the plate, said gear and rack being one connected and movable with the support, and the other being fixed and with relation to which the support has a relative movement, and means for automatically rendering the first said means active and inactive, at predetermined points in the movement of the plate. 115
37. Article feeding mechanism for slicing machines, embodying a reciprocating support, a feed plate connected therewith, means for moving the plate relatively to the support, the said means embodying a rack and gear, and normally inactive with respect to the plate, said gear and rack being one connected and movable with the support, and the other being fixed and with relation to which the support has a relative movement, and means for automatically rendering the first said means active and inactive, at predetermined points in the movement of the plate. 120
38. Article feeding mechanism for slicing machines, embodying a reciprocating support, a feed plate connected therewith, means for moving the plate relatively to the support, the said means embodying a rack and gear, and normally inactive with respect to the plate, said gear and rack being one connected and movable with the support, and the other being fixed and with relation to which the support has a relative movement, and means for automatically rendering the first said means active and inactive, at predetermined points in the movement of the plate. 125
39. Article feeding mechanism for slicing machines, embodying a reciprocating support, a feed plate connected therewith, means for moving the plate relatively to the support, the said means embodying a rack and gear, and normally inactive with respect to the plate, said gear and rack being one connected and movable with the support, and the other being fixed and with relation to which the support has a relative movement, and means for automatically rendering the first said means active and inactive, at predetermined points in the movement of the plate. 130

machines, embodying a reciprocating support, a feed plate movable with respect thereto, a guide for the support provided with a rack portion, a pinion movable with 5 the support and rotatable with respect thereto, said pinion meshing with the rack, said rack and pinion being normally inactive with respect to the plate, means controlled by the plate for connecting and disconnecting the pinion with the feed plate.

33. Article feeding mechanism for slicing machines, embodying a reciprocating support, a feed plate movable therewith and with respect thereto, a rack adjacent the support, a pinion carried with the support and meshing with the rack, said rack and pinion being normally inactive with respect to the plate, and means responsive to the movement of the plate with respect to the support, for 15 automatically connecting and disconnecting the pinion and feeding plate.

34. Article feeding mechanism for slicing machines, embodying a reciprocating support, a feed plate movable therewith and with respect thereto, a rack adjacent the support, a pinion carried with the support and meshing with the rack, said rack and pinion being normally inactive with respect to the plate, and means responsive to the 25 movement of the plate for automatically connecting and disconnecting the pinion and feeding plate, all of said parts being arranged below the plate.

35. Article feeding mechanism for slicing machines, embodying a reciprocating support, a feed plate movable therewith and with respect thereto, a rack adjacent the support, a pinion carried with the support and meshing with the rack, and means controlled 30 by the movement of the plate with respect to the support for rendering the rack and pinion active and inactive with respect to the plate.

36. In a slicing machine, a reciprocating support, a feed plate, an element rotatable about an upright axis for advancing and returning the plate, a prime mover for said element, means for actuating the prime mover in one direction, means for actuating 45 the prime mover in the opposite direction, one of the said means embodying a gear and rack, and mechanism common to the said means for rendering them active with respect to the prime mover.

37. In a slicing machine, a reciprocating support, a feed plate, an element rotatable about an upright axis for advancing and returning the plate, a prime mover for said element, means for actuating the prime 50 mover in one direction, means for actuating the prime mover in the opposite direction, one of the said means embodying a gear and rack, and mechanism controlled by the movement of the plate for automatically render-

ing both of the said means active and inactive with relation to the said prime mover.

38. In a slicing machine, a reciprocating support, a feed plate, an element rotatable about an upright axis for advancing and returning the plate, a prime mover for said element, means for actuating the prime mover in one direction, means for actuating the prime mover in the opposite direction, one of the said means embodying a gear and rack, mechanism common to the 75 said means for automatically rendering them active and inactive with relation to the prime mover, and manual means for also actuating the said prime mover.

39. In a slicing machine, a support having 80 a forward and a backward movement, a feed plate carried therewith and movable with respect thereto, means for advancing the feed plate, with respect to the support, and means responsive to the movement of 85 the plate and automatically rendered operative for returning the plate.

40. In a slicing machine, a reciprocating support, a feed plate carried therewith, means for advancing the feed plate with respect to the support, and means adapted to be set by the movement of the plate and operating to automatically return the feed plate.

41. In a slicing machine, a reciprocating 95 support, a feed plate carried therewith, means for advancing the feed plate with respect to the support, and positive means automatically rendered active at a predetermined point in the advancement of the 100 plate for returning the plate.

42. In a slicing machine, a reciprocating carriage, a feeding plate and a meat plate, both plates supported directly by the carriage.

43. In a slicing machine, a reciprocating carriage, a feeding plate, and a meat plate, both plates having direct sliding bearings upon the carriage.

44. In a slicing machine, a reciprocating 110 carriage, a feeding plate slidably upon the carriage, means detachably connecting the plate with the carriage, and a meat plate slidable upon the carriage.

45. In a slicing machine, a reciprocating 115 carriage, a feeding plate having a sliding bearing upon the carriage, a meat plate also having a sliding bearing upon the carriage, and means detachably connecting the plates.

46. In a slicing machine, a reciprocating carriage, a feeding plate slidably supported by the carriage, means disposed below the plate for moving it, a meat plate slidably supported by the carriage, and provisions for connecting the plates for movement in 120 unison with respect to the carriage.

47. In a slicing machine, a reciprocating carriage, a feeding plate slidably supported

thereby, provisions for moving the plate embodying operating mechanism, a portion of which is arranged above and a portion below the carriage, and means for automatically controlling the direction of movement of the feeding plate by the said operating mechanism.

48. In a slicing machine, a reciprocating carriage, a feeding plate, and a meat plate, both of said plates being supported directly by the carriage and independently with respect to each other.

49. In a slicing machine, a reciprocating carriage, a feeding plate, and a meat plate, both of said plates being slidably supported directly by the carriage and independently with respect to each other.

50. In a slicing machine, a reciprocating support, a guide rail for the support, a feed plate carried with the support, means for advancing the plate with respect to the support, and positive means operatively related

to the guide rail and automatically rendered active at a predetermined point in the advancement of the plate for returning the plate.

51. In a slicing machine, a reciprocating support, a guide rail for the support, a feed plate carried with the support, means for advancing the feed plate with respect to the support, and means connected with the support and guide rail and automatically rendered active at a predetermined point in the advancement of the plate for returning the plate.

In testimony whereof I have signed my name to this specification, in the presence of two subscribing witnesses, on this 16th day of July, A. D. 1913.

HENDRIK STUKART.
